UNITED STATES PATENT OFFICE.

HARDY S. FERGUSON, OF NEW YORK, N. Y., ASSIGNOR TO GREAT NORTHERN PAPER COMPANY, OF MILLINOCKET, MAINE, A CORPORATION OF MAINE.

PAPER-MAKING MACHINE.

Application filed December 16, 1921. Serial No. 522,749.

To all whom it may concern:

Be it known that I, HARDY S. FERGUSON, a citizen of the United States, residing at New York city, in the county of New York and State of New York, have invented an Improvement in Paper-Making Machines, of which the following is a specification.

This invention relates to means for driving a stack of driers, for instance those used in a paper machine.

The usual method of driving a stack of driers is to mount a spur gear on the end of one of the two journals of each drier, and to arrange them with their axes parallel to each other in such a manner, that the gears mesh together successively, forming one or more trains or series, each containing sometimes as many as ten driers. Power for operating each train of a stack of driers is applied through the driving gears to the first gear of each train.

In this system the power required to rotate any given drier is transmitted through all of the gears of the train in which it is located, which are between it and the driving gear, and the amount of power which must be supplied by the driving gear for this purpose is equal to that actually consumed at the drier, divided by the product of the efficiencies of every gear contact through which it passes.

Since these efficiencies are always less than 100%, the actual amount of power to be supplied by the driving gear for rotating a drier which is remotely located from the beginning of the train, is greater than the amount which must thus be supplied to rotate the first in the train, and the difference increases very rapidly the further the drier is located from the driving gear.

An object of this invention is to provide the drier section of a paper-making machine with driving means including a driving shaft co-extensive with the driers and independently rotatably connected positively with each drier of the section whereby each drier will be independently driven positively and yet all driers will be constrained to rotate at equal speeds.

In carrying out my invention, I may extend a driving shaft midway between and co-extensive with the banks of driers. Worms may be fixed to said shaft which may mesh independently with worm gears fixed to the driers. Power for rotating the shaft to rotate the driers may be applied to the shaft in any suitable manner.

Fig. 1 is a side elevation of the drier section of a paper-making machine with my invention applied thereto.

Fig. 2 is an enlarged sectional detail, taken along line 2—2 of Fig. 3, and illustrating the manner of driving the driers of both banks from the common drive shaft.

Fig. 3 is an enlarged detail taken along line 3—3 of Fig. 1.

Fig. 4 is a side elevation similar to Fig. 1 showing the invention applied to staggered driers.

My invention is particularly adapted for driving banks of driers wherein the driers of the upper bank are vertically arranged over the driers of the lower bank, and will be described in combination with such an arrangement of driers although the invention is not limited to such an arrangement.

As here shown, the driers 10 are arranged in two superimposed banks. The shafts 11 of said driers are rotatably supported in suitable bearings 12 in the frame 13 and extend beyond said frame to receive driving worm gears. The paper web is adapted to enter the drier section at the left and pass between the end lower drier and the lower felt 14 and pass about said lower drier and thence upwardly between the upper end drier and the upper felt 15 and thence downward to the next lower drier and so on.

A driving shaft 16 is extended along the banks of driers midway between the upper and lower driers and is rotatably supported in suitable bearings 17. Said shaft may be driven by any suitable means, as by a pulley 18 at one end of said shaft or by a pulley 19 intermediate the ends of the shaft, and disposed between the driers, or both. Said shaft may be supported

against axial displacement due to the thrust of gears hereinafter to be described by suitable means as by the thrust bearing 20.

Worm, or equivalent, in which term I include spiral, gears 21 are fixed to the ends of the drier shafts 11 which extend beyond said frame. Worms, or it may be spiral gears, 22 are fixed to said driving shaft 16 and each worm 22 is arranged to mesh with the gear of an upper and corresponding lower drier and consequently drive both driers. The pitch of the worms is high to give greater efficiency.

With this arrangement, each drier is driven by its gear wheel from a worm on the power shaft with which it is directly geared, and no drier gear wheel takes any part in driving any other drier. Nevertheless, though each drier has an individual connection with the power shaft, all the driers of the section are positively connected so that they must rotate at equal speeds.

The arrangement above set forth is more satisfactory than the train of gears now in use, in that no more power is required to drive the remote driers of the section than is required to drive the first drier. Where a train of gears is used, and the first drier is driven from the main drive shaft, the second by gears from the first and so on, the loss of power by gear friction increases very rapidly with the number of dryers in a train, and the average or combined efficiency of the entire train of gears is much less than the efficiency of a single pair of gears.

On the contrary with the worm gear system of driving each drier directly from the power shaft, the combined efficiency of the gears of a bank of driers as a whole is substantially the same as that of an individual gear and its driving worm.

The worms and worm gears are preferably enclosed in a casing 25 which may contain a bath of oil by which the gears are lubricated, although other well known means for lubrication may be employed, and the casing preferably is made substantially oil tight to prevent undue oil leakage.

The arrangement above set forth has, in addition to greater efficiency than the drive through a train of spur gears, the advantages of comparative freedom from noise, reduction in back-lash between the remote driers of the section, and decreased strain upon the driving gears; as contrasted with the usual spur-gear-train system of driving the driers.

It must be remembered, however, that the theoretical efficiency of my system, or other systems, is never obtained and that poor workmanship on the gears may destroy the theoretical advantage of my system as compared with gears of perfect workmanship otherwise arranged.

In Fig. 4, I show my invention applied to

the usual staggered driers wherein the upper driers 30 are staggered with respect to the lower driers 31. The drive shaft 32 is extended longitudinally between the driers, as before, but in this modification, separate worms 33 are carried by the shaft for the drier and mesh with the worm gears 34 of the driers. A suitable thrust bearing 35 may be employed to restrain the shaft 32 from axial movement due to unbalanced thrust between the worms and worm gears.

Other modifications may readily be conceived.

I claim:

1. A paper-making machine having a plurality of driers about which the paper web is passed in succession to be dried, and driving means for said driers including a plurality of driving devices each arranged in positive driving engagement with a pair of driers.

2. A paper-making machine having a plurality of driers disposed in two superposed rows and between and about which driers the paper web is passed in succession to be dried, and driving means for said driers including a common drive shaft extended between and adjacent said driers, and a plurality of driving devices each arranged to be driven directly from said common drive shaft.

3. A paper-making machine having a plurality of driers disposed in two superposed rows and between and about which driers the paper is passed in succession to be dried, a drive shaft extended between and adjacent said driers, worm gears carried by said driers, and worms carried by said shaft each in mesh with the worm gear of a drier.

4. A paper-making machine having a plurality of driers about which the paper is passed in succession to be dried, and driving means for said driers including a drive shaft extended adjacent said drier, worm gears carried by said driers, and worms carried by said shaft in mesh with the worm gears of said driers, each worm common to two adjacent drier worm gears.

5. A paper-making machine having a plurality of driers arranged in two superimposed banks with the driers of the upper bank vertically disposed over the driers of the lower bank, and positive driving means for said driers comprising a drive shaft disposed between said banks of driers, worm gears carried by said driers, and worms carried by said drive shaft meshing with the worm gears of pairs of vertically disposed driers.

6. A paper-making machine having the combination of a frame, a plurality of driers rotatably supported in said frame in two superimposed banks with the driers of the upper bank vertically disposed over the

driers of the lower bank, said driers having shafts extended beyond said frame on one side, worm gears fixed to said shafts beyond said frame, a drive shaft extended midway between said worm gears, worms fixed to said shaft each arranged independently to mesh with the worm gears of a pair of ver-

tically aligned driers and housings enclosing each pair of worm gears and a common worm.

In testimony whereof, I have signed my name to this specification.

HARDY S. FERGUSON.
